JOSIAH FRANCIS JOHNSON, OF EDGEWOOD, PENNSYLVANIA, ASSIGNOR TO THE WESTINGHOUSE MACHINE COMPANY, A CORPORATION OF PENNSYLVANIA.

AUTOMATIC VALVE MECHANISM.

1,223,340.

Specification of Letters Patent. Patented Apr. 17, 1917.

Application filed August 19, 1914. Serial No. 857,530.

To all whom it may concern:

Be it known that I, JOSIAH FRANCIS JOHNSON, a citizen of the United States, and a resident of Edgewood, in the county of Allegheny and State of Pennsylvania, have made a new and useful Invention in Automatic Valve Mechanism, of which the following is a specification.

This invention relates to multi-stage turbines or engines and has for an object to produce improved means for bleeding motive fluid from a working passage of a turbine or engine.

A further object is to produce an improved bleeder valve mechanism for delivering motive fluid from an intermediate pressure working stage of a turbine or engine, in which means are employed for proportioning the delivery of fluid through the valve mechanism to a low pressure stage of the turbine or engine in response to variations in the pressure of the fluid delivered from the intermediate pressure stage.

A further object is to produce an improved bleeder valve mechanism for delivering motive fluid from a low pressure stage or working passage of a turbine or engine, which is responsive in its operation to variations in the load on the turbine or engine.

These and other objects I attain by means of an apparatus embodying the features herein described and illustrated in the drawings accompanying and forming a part of this application.

In the drawings, Figure 1 is a vertical sectional view of a multi-stage turbine equipped with a valve mechanism embodying my invention.

Fig. 2 is a sectional view on an enlarged scale of the valve mechanism illustrated in Fig. 1.

My invention, as embodied in the apparatus illustrated, consists of a valve mechanism adapted to supply steam for heating or industrial purposes from an intermediate stage of a turbine to a delivery port or passage which communicates with a heating system or industrial apparatus employing low or intermediate pressure steam. The valve also controls the delivery of steam from the intermediate stage to a working stage of low pressure of the turbine, and is responsive in operation to variations in the

pressure of the steam delivered to the delivery port or passage. Through certain ranges of load on the turbine the valve mechanism is responsive, in its operation, to variations in the load on the turbine and is adapted to close the delivery port or passage when the load conditions are such that the turbine cannot carry the load and supply steam through the delivery port or passage for heating or industrial purposes.

In Fig. 1, I have illustrated a multi-stage turbine, including an initial stage 3, receiving motive fluid through a passage 4, from a governor controlled valve mechanism 5, and delivering motive fluid to an intermediate stage 6. The motive fluid discharged from the intermediate stage 6 is received by an annular chamber or passage 7, formed within the turbine casing, and is adapted to be delivered through a delivery port 8 for heating or industrial purposes, or through a series of ports 9 to an annular chamber or passage 10, which communicates with the inlet of a low pressure stage 11 of the turbine. The delivery of fluid through the port 8, to the exterior of the turbine, or through the series of ports 9, to the low pressure stage of the turbine, is controlled in the illustrated embodiment of the invention, by a cylindrical balanced valve 13, which operates within a cylindrical casing 13^a, provided with a series of ports 14, which communicate with the port 8, and the ports 9, which communicate with the low pressure stage 11.

The valve 13 is so proportioned and so located within its casing that the ports 9 are opened as the ports 14 are closed and vice versa, the ports 9 are closed as the ports 14 are opened, and one set of ports is fully closed when the other is fully open. In the illustrated embodiment of the invention, the valve 13 is actuated by a pressure responsive agent, illustrated as a plunger 15, which is located within a cylinder 16, having one end in communication with the port 8, through the port or passage 17, and the other end in communication with the atmosphere through a port 18, so that the plunger is adapted to move in response to varying pressures delivered through the passage 17 and to thereby proportion the delivery of motive fluid from the chamber 7, through the ports 9.

and 14, so as to maintain a substantially constant pressure in the fluid delivered through the port 8 or, in other words, to proportion the delivery of fluid from the chamber 7 between the port 8 and the low pressure stage 11, in response to variations in the pressure of fluid delivered through the port 8.

The stem 15^a of the plunger 15 is shown 10 connected to one end of a lever 21, by means of a suitable link 22, and the lever is pivotally mounted on the stem 23 of the valve 13. The other end of the lever is pivotally connected to a link 24, which in turn is pivotally connected to the rod 26 of a fluid or hydraulically actuated piston 26, which will hereinafter be described. I preferably provide a coiled spring 19, for opposing the fluid pressure on the plunger 15, so that the 15 plunger and consequently the valve 13 will move to definite positions corresponding to different pressures of the fluid delivered through the port 8. A suitably proportioned or adjustable weight may be substituted for the spring 19.

The operation of the valve 13 in response to variations in the pressure of the fluid delivered by it through the port 8 is as follows: As long as the pressure of the fluid 20 traversing the port 8 is below a determined or desired pressure, the valve 13 will remain in its lowest position, in which the ports 9 are fully closed and the ports 14 are fully opened. All the motive fluid delivered from 25 the intermediate or secondary stage 6 of the turbine will therefore be delivered through the ports 14 and the port 8. As the steam delivered from the stage 6 exceeds the demand for steam made upon the port 8, the 30 pressure of the fluid passing the port 8 will increase and after a predetermined pressure is reached the plunger 15 will start to move upwardly in response to the increasing pressure of motive fluid delivered through the 35 passage 17, and will lift the valve 13, thereby throttling the ports 14 and partially opening the ports 9, so that a portion of the motive fluid from the chamber 7 is delivered to the port 8 and a portion is delivered to 40 the low pressure stage 11 of the turbine. The valve 13 is raised by the plunger 15 through the agency of the lever 21, which then fulcrums about its pivotal connection with the link 24. The spring 19 may be 45 provided with means for adjusting its tension, and consequently for regulating the automatic operation of the valve 13; it may also be replaced by an adjustable weight or weights arranged to proportion the lift of 50 the valve 13 to the pressure of the fluid delivered to the cylinder 16, or it may be weighted so that the plunger 15 and consequently the valve 13 will always move to one extreme position or the other and consequently fully open or fully close the ports 55 60 65

14. Such an arrangement, however, is not desirable for installations in which the turbine is subjected to variable loads, and in which the pressure in the chamber 7 will fluctuate.

The illustrated embodiment of the invention is also provided with means such that if the load on the turbine increases to such an extent that the turbine cannot carry it and also supply motive fluid through the port 8, 75 the valve 13 will move to close the ports 14, thereby shutting off the supply of motive fluid to the port 8, and open the ports 9 delivering all the fluid from the stage 6 to the low pressure stage 11. This is accomplished 80 in the illustrated embodiment by means of the piston 26, which is controlled by a relay valve 27. The valve 27 is in turn controlled by the turbine governor, through a lever 28. As illustrated, the governor rod 29 is operatively connected to a lever 31, which is fulcrumed on a bracket 32, of the turbine casing, and is operatively connected to the admission valve 5 of the turbine, by means of a link 33, so that the governor proportions 90 the delivery of motive fluid to the turbine in response to variations in the speed of or the load on the turbine. With such an arrangement the valve 5 will be opened as the speed of the turbine decreases and the governor 95 shifts the rod 29 in the direction indicated by the arrow in Fig. 2. The lever 31 is shown as connected, through the agency of an adjustable lost motion connection 34, with the lever 28 by means of which the relay valve 27 is actuated, and the lost motion connection is so adjusted that a further motion of the lever 31, after the valve 5 has been moved to deliver a maximum amount of motive fluid to the turbine, will shift 105 the relay valve 27 and thereby move the valve 13 to throttle or close the ports 14.

The relay valve 27 is of the usual construction and receives fluid or liquid under pressure through a port or passage 35. Delivery of liquid to and the discharge of liquid from each end of the cylinder 36, in which the piston 26 is mounted, is controlled by the valve 27, so that the piston is shifted by the liquid pressure in response to variations in the position of the relay. When the relay 27 is moved downwardly, in response to a decrease in speed of the turbine, it establishes communication between the inlet port 35 and a port 37 leading to the lower 110 end of the cylinder 36 and also establishes communication between a passage 38 leading from the upper end of the cylinder 36 and a discharge port 39. An upward movement of the piston 26 will lift the valve 13, 115 through the agency of the lever 21 which, during the operation of the piston 26, will fulcrum around its pivotal connection with the link 22. Inasmuch as the lever 28 is connected to the stem 23 of the valve, mo- 120 125 130

tion of the valve will shift the position of the relay 27 and consequently each definite position of the relay actuating lever 31 will cause the valve 13 to occupy a definite position with relation to the ports 9 and 14 and consequently the valve 13 will operate to throttle the ports 14, as the load on the turbine increases beyond a certain predetermined load, and to deliver increasing amounts of motive fluid to the final stage of the turbine.

With the apparatus illustrated, the valve 13 will operate in response to variations in the pressure of fluid delivered through the bleeder port 8 during normal loads on the turbine, but will be governor controlled, or will operate in response to variations in the load on the turbine when the turbine is subjected to abnormal or overloads. The load responsive operation of the valve 13 is independent of the demand for steam upon the bleeder port 8, and consequently when the turbine is subjected to a determined overload, the relay 27 will operate to lift the valve 13 to fully close the ports 14 and fully open the ports 9 independently of the operation of the plunger 15.

It will be apparent to those skilled in the art that the intermediate or secondary stage 6 of the turbine disclosed, is the equivalent of an independent high pressure element, such for example, as a turbine or a reciprocating engine receiving steam or motive fluid from any source of high pressure, and discharging at atmospheric or any determined relatively low pressure. It will also be apparent that the low pressure stage 11 is the equivalent of an independent low pressure engine or turbine operating on low pressure steam or motive fluid received from any source. With this in mind it is evident that a valve embodying the features herein described may be employed in proportioning the delivery of motive fluid from any high pressure element to any low pressure engine or turbine and to a bleeder port through which fluid is delivered for heating or commercial purposes. It will also be evident that the valve mechanism may be employed in connection with apparatus, such as described above, but in which the bleeder port connects directly with the condenser, for the purpose of bypassing steam or fluid around the low pressure engine or turbine and delivering it directly to the condenser for the purpose of giving the high pressure element the benefit of exhausting into the condenser when the load conditions are such that the demand for steam or fluid on the low pressure engine is reduced.

It will also be understood that my invention may be employed with various types of turbines or multi-stage or compound engines, that motive fluid may be bled from any stage of the turbine or engine and that

various means may be employed for effecting the load responsive control of the bleeder valve. It will also be apparent to those skilled in the art that various changes, modifications, substitutions, omissions and additions may be made in the valve mechanism illustrated, to meet the requirements of different installations and that the proportioning of the delivery of fluid from the chamber 7 to the bleeder port and to the low pressure stage of the turbine may be accomplished in various ways, without departing from the spirit and scope of my invention as set forth by the appended claims.

What I claim is:

1. In combination with an engine having a fluid delivery port for bleeding steam from a low pressure working passage thereof, a valve for controlling the delivery of fluid through said port, means responsive to variations in the pressure of fluid delivered through said port for controlling the operation of the valve, and a governor mechanism for controlling the delivery of motive fluid to the engine and for controlling the operation of the valve independent of said means.

2. In combination with a multi-stage turbine having a fluid delivery port for bleeding steam from an intermediate pressure stage of the turbine, a valve mechanism for controlling the delivery of fluid through the port and for delivering fluid from the intermediate stage to a low pressure stage of the turbine, means responsive to the variations in pressure of the fluid delivered to said port for controlling the operation of the valve mechanism during normal loads on the turbine, and load responsive means for controlling the operation of the valve independently of the pressure responsive means during abnormal or overloads on the turbine.

3. In combination with a multi-stage turbine, having a port for bleeding steam from an intermediate pressure stage, a single valve for controlling the delivery of steam through the port and for delivering steam from the intermediate stage to a low pressure stage of the turbine, said valve being so arranged that the flow of steam to said port is increased as the flow to the low pressure stage is decreased and the flow to the low pressure stage is increased as the flow to the port is decreased, means responsive to the pressure of fluid delivered to the port for controlling the operation of said valve, and a governor mechanism for controlling the delivery of steam to the turbine and for controlling the operation of said valve independently of said means.

4. In combination with a multi-stage turbine, having a port for bleeding steam from an intermediate pressure stage of the turbine, a single valve for controlling the de-

livery of fluid through the port and for delivering fluid from the intermediate stage to a low pressure stage of the turbine, means responsive to the pressure of fluid delivered by said valve to said port for controlling the operation of the valve, and load responsive means for controlling the operation of the valve independently of the pressure responsive means.

10 5. A turbine, having a port for delivering fluid from a working passage thereof of intermediate pressure, in combination with a low pressure turbine stage for receiving fluid from said passage of intermediate pressure, a single valve for controlling the delivery of fluid through said port and to said low pressure stage, means responsive to the pressure of the fluid delivered through said port for controlling the operation of said valve, and means responsive to the speed of the turbine for actuating said valve to close said port independently of the operation of said pressure actuated means.

6. In combination with an engine having 25 a fluid delivery port communicating with a working passage of intermediate pressure, and a working passage of lower pressure adapted to receive fluid from the passage of intermediate pressure, a valve mechanism 30 for proportioning the delivery of fluid to said port and to said working passage of lower pressure, means responsive to the pressure of fluid delivered through said port for controlling the operation of said valve mechanism, and means responsive to 35 variations in the speed of the engine for actuating the valve mechanism, independently of the operation of the pressure responsive means, to close said port when the 40 load on the engine exceeds a determined load.

7. In combination with a multi-stage turbine, having a fluid delivery port communicating with a stage of intermediate pressure, a valve for controlling the delivery of 45 fluid from said stage through said port and from said stage to a stage of lower pressure, a pressure actuated plunger for controlling the operation of the valve responsive to variations in the pressure of fluid delivered 50 to said port, a piston for controlling the operation of the valve independently of said plunger, and a governor-controlled relay for controlling the operation of said piston.

8. In combination with a multi-stage turbine, having a fluid delivery port communicating with a stage of intermediate pressure, a valve for proportioning the delivery of fluid to said port and to a stage of the 55 turbine of lower pressure, a pressure actuated plunger responsive to the pressure of the fluid delivered to the port, for controlling the operation of the valve, a piston for controlling the operation of the valve independently of the plunger, a governor-controlled relay for controlling the opera-

tion of said piston, and a governor for controlling the operation of the relay and the delivery of fluid to the engine.

9. In combination with an engine having a fluid delivery port communicating with a working passage of intermediate pressure, and a working passage of lower pressure adapted to receive fluid from the passage of intermediate pressure, an inlet valve for delivering fluid to the passage of intermediate pressure, means for controlling the delivery of fluid through the delivery port, and to the passage of lower pressure, an agent responsive to the pressure of fluid delivered through the port for controlling the operation of said means, and a governor mechanism responsive to variations in the speed of the engine for controlling the operation of said inlet valve and for actuating said means to close said port, and to establish communication between said working passages after said inlet valve is fully open.

10. In combination with a multi-stage turbine having a bleeder port communicating with a stage of intermediate pressure, and a stage of lower pressure adapted to receive fluid from said intermediate pressure stage, an inlet valve for the turbine, means for controlling the delivery of motive fluid through said port and to the stage of lower pressure, a governor mechanism responsive to the speed of the turbine for controlling the operation of said valve and for controlling the operation of said means whereby the delivery of fluid through said port is decreased and the delivery of fluid to said stage of lower pressure is increased in response to a decrease in speed of the turbine and after the inlet valve is fully open.

11. In combination with a multi-stage turbine having a bleeder port communicating with a stage of intermediate pressure, and a stage of lower pressure adapted to receive fluid from said intermediate pressure stage, an inlet valve for the turbine, means for controlling the delivery of motive fluid through said port, and to the stage of lower pressure, an agent responsive to the pressure of the fluid delivered through said port for controlling the operation of said means to increase the delivery of fluid to the port and decrease the delivery of fluid to said stage of lower pressure in response to a reduction in pressure at said port, and for increasing the delivery of fluid to said stage of lower pressure and decreasing the delivery of fluid to said port in response to an increase in pressure at said port, and a governing mechanism responsive to the speed of the turbine for controlling the operation of said valve and said means, said governing mechanism having no active controlling effect.

on said means during normal speeds of said turbine.

12. In combination with a multi-stage turbine having a bleeder port communicating with a stage of intermediate pressure, and a stage of lower pressure adapted to receive fluid from said intermediate pressure stage, an inlet valve mechanism for delivering motive fluid to the turbine, means for controlling the delivery of fluid from the intermediate stage to said port or to said stage of lower pressure, a pressure responsive agent for controlling the operation of said means, a governor responsive to the speed of the turbine for controlling the operation of the inlet valve mechanism, and means actuated by the governor after the speed of the turbine has decreased a determined amount for controlling the operation of said first mentioned means to close off communication between the intermediate stage and the port and to establishing communication between the intermediate stage and the stage of lower pressure.
13. In combination with a multi-stage turbine having a bleeder port communicating with a stage of intermediate pressure, and a stage of lower pressure adapted to receive fluid from said intermediate pressure stage, an inlet valve for controlling the delivery of fluid to the turbine, means for controlling the delivery of fluid from said intermediate pressure stage to said port and to said stage of lower pressure, and a governing mechanism responsive to the speed of the turbine for controlling the operation of said inlet valve and for closing communication between the intermediate pressure stage and the port and establishing communication between the intermediate pressure stage and the stage of lower pressure, when the turbine falls below a determined speed.

14. In combination with a multi-stage turbine having a bleeder port communicating with a stage of intermediate pressure, and a stage of lower pressure adapted to receive fluid from the stage of intermediate pressure, means for controlling the delivery of fluid to the bleeder port and to the stage of lower pressure, a governing mechanism responsive to the speed of the turbine for actuating said means to close said port when the turbine falls below a determined speed, said mechanism having no active controlling effect on said means while the turbine is operating at normal speeds.

15. In combination with a multi-stage turbine having a bleeder port communicating with an intermediate pressure stage, and a low pressure stage adapted to receive fluid from the intermediate pressure stage, means for controlling the delivery of fluid from the intermediate stage to said port and to the low pressure stage, an agent responsive to the pressure at the port for controlling said means to increase the delivery of fluid to the port and decrease the delivery of fluid to the low pressure stage in response to a decrease in pressure at the port and to increase the delivery of fluid to the low pressure stage and decrease the delivery of fluid to the port in response to an increase in pressure at the port, a governing mechanism responsive to the speed of the turbine for controlling said means to close said port and establish communication between said stages when the turbine speed decreases below a determined speed.

In testimony whereof, I have hereunto subscribed my name this 17th day of August, 1914.

J. FRANCIS JOHNSON.
